UNITED STATES PATENT OFFICE

MEIER GEO. HILPERT, OF BETHLEHEM, PENNSYLVANIA

TRACKWAY

Application filed October 10, 1927. Serial No. 225,268.

This invention relates to an improvement in trackways, and more particularly to what may be termed a permanent track construction.

5 To that end the invention contemplates a rigid construction especially adapted for round-house pits, cinder pits, transfer tables, circular turn-tables, tunnels, mountain grades, snow sheds, train sheds and the like 10 where it is desirable to rigidly mount the rails on the roadbed to resist creeping and provide a maximum support for the bases of the rails.

A primary object of the invention is, 15 therefore, to provide a permanent roadbed together with means for securing the rails to such bed in a novel and effective manner to meet all conditions of use in installations of the type above referred to. That is to 20 say, it is proposed to provide a metal to metal contact between the rail and a part of the roadbed, and to locate the fastening means for the rail away from and independent of the tie locations thereby to permit 25 of fastening the rails to the ties by a given load. In that connection it is proposed to provide a construction which permits of alining and adjusting the ties, reinforcing 30 elements, rails and rail fastenings in a practical and expeditious manner before the concrete is poured, thereby providing a rigid self sustaining structure which can be easily and effectively anchored in the concrete bed.

A further object of the invention is to 35 provide a simple and practical roadbed construction which permits of the utilization of old or worn rails or rolled sections of a similar type, thereby taking the factor of economy into consideration while at the 40 same time utilizing the otherwise unserviceable parts in a manner to provide ample strength and security and also protection against further deterioration by rusting in the construction of the roadbed.

45 With the above and other objects in view which will more readily appear as the nature of the invention is better understood, the same consists in the novel construction, combination and arrangement of parts herein-

after more fully described, illustrated and claimed.

A preferred and practical embodiment of the invention is shown in the accompanying drawings, in which:—

55

Figure 1 is a vertical cross sectional view of the improved construction.

Figure 2 is a vertical longitudinal sectional view of the construction shown in Figure 1, the same showing a portion of 60 the concrete in place.

Figure 3 is a detail vertical sectional view taken on the line 3—3 of Figure 2.

Figure 4 is a side elevation of the roadbed construction and a part of the concrete, the 65 same also illustrating a modified form of rail fastening device.

Figure 5 is a vertical sectional view taken on the line 5—5 of Figure 4.

Figure 6 is a side elevation of a portion 70 of the roadbed and track showing a still further modified form of rail fastening device.

Figure 7 is a detail vertical sectional view taken on the line 7—7 of Figure 6.

75

Figure 8 is a detail view of a type of rail engaging clip that may be used to secure the rail in position.

Figure 9 is a plan view of an adjustable washer adapted to be used in connection with 80 the lateral adjustment of the rails.

Figure 10 is a top plan view of the clip shown in Figure 8.

Figure 11 is a plan view of a modified form of washer which affords a wider range 85 of adjustment between the edge of the rail and the shank of the bolt element of the rail fastening device.

Figures 12 and 13 are respectively top plan and vertical sectional views of a circular form of rail engaging clip.

Figure 14 is a detail longitudinal sectional view of a portion of an old bed and new roadbed and track, illustrating another type of rail fastening and the manner of effecting its emplacement in the old permanent roadbed.

Figure 15 is a vertical sectional view taken on the line 15—15 of Figure 14.

Figure 16 is a view similar to Figure 15.

100

showing a still further modified form of construction.

Figure 17 is a detail vertical longitudinal sectional view illustrating the manner in which the ends of the rails may be supported at the bottom and welded at the top to secure maximum rigidity at the rail ends.

Similar reference characters designate corresponding parts throughout the several figures of the drawings.

In carrying the present invention into effect it is proposed to provide a track construction wherein the roadbed or track-bed is made in a thoroughly practical and substantial manner to hold the tie elements rigidly and securely in position to support the rails. In that connection it is proposed to disassociate the rail fastenings from the ties by locating them in the permanent bed structure so that the rails will be flexed or pulled downwardly at points between the tie locations in such a way as to make the tie elements in effect a fulcrum about which the metal of the rails bends when the clamps or fastenings are applied. Thus, the present construction aims to provide an arrangement which fastens the rails under clamp tension to prevent wave motion in the rails and so that the impact of the traveling load falling from one rail to another is entirely obviated because of the rigidity of the construction and its being under an initial loading throughout.

By way of illustrating the manner in which the invention may be carried into effect, reference may be made to Figures 1 and 2 of the drawings which show a pair of running rails R resting upon the tie elements T, the same preferably being suitable metallic members such for example as old rails which may be used with their base portions inverted while the head portions thereof may be welded as indicated at W to the relatively short tie-footing members T'. The ends of the ties T and the footings T' are preferably burned to a bevel cut as shown in Figure 1 thereby to provide additional anchoring means for these members in the concrete bed and to distribute the load for a given length or weight of rail over a greater area of earth, ground or other surface on which the track is built.

In preparing the present construction, it is proposed to fully assemble and adjust the rails R and tie elements T before the concrete C is poured, and to that end the said tie elements T and their footings T' may be mounted on any suitable and convenient supports 1 which may be bricks or their equivalent that remain in the permanent bed when the concrete is poured, but serve to temporarily hold the tie elements in the proper elevated position to permit of adjusting and placing the reinforcing elements and the anchoring elements for the rail fasten-

ing means. Any suitable form of reinforcement may be utilized to provide strength and rigidity for the roadbed, but by way of illustrating a preferred arrangement of such reinforcing elements, it will be observed from the drawings that the reinforcing rods 2 may be carried by any convenient support such as a brick or block 3 to space the reinforcing elements from the bottom of the pit or the like to permit the concrete to be tamped therebeneath.

Referring now more particularly to the means for fastening or securing the rails R in position on the tie elements T, it will be observed that the same includes primarily, 80 suitable anchoring rods 4 which extend continuously beneath a series of ties and engage with suitable spacing elements 5 arranged beneath the tie footing T'. The said spacing elements provide in effect a plurality of fulcrum points at the tie locations for the rods to engage so that they may be readily bent and placed under tension during the rail fastening or securing operation. As shown in Figures 1, 2 and 4, the anchoring 90 rod spacing members 5 are preferably in the form of angle sections which may be set against or welded to the underside of the footings T'. On the other hand a piece of rock or brick or its equivalent may be used to provide a spacing point for the anchoring means which will be well below the tie footings thereby to permit of the concrete to be filled in between the anchoring members and the bottoms of the footings as will be apparent from Figures 1 and 2, to provide additional anchoring strength for the rods 4.

The rail fastening device designated generally as F essentially includes a clip or nut receiving yoke 6 and an adjustable anchor member 7. In the form shown in Figures 2 and 3, the said yoke 6 is preferably in the form of a substantially "V-shaped" loop, the upper ends of the arms of which are adapted to receive rail engaging clips 8 for securing the rails to the tie members while the lower end or bight thereof is adapted to receive the hook portion 9 of the adjustable anchor 7. The shank portion of the said anchor 7 is threaded as indicated at 7^a and receives thereon a nut 7^b which is adapted to cooperate with a bearing member 10 which may be in the form of an angle section one of whose flanges fits over the shank of the member 7, so that by adjusting the nut 7^b the anchor 6 may be pulled downwardly while the rods 4 may be pulled upwardly, thereby serving to place the rail R under permanent bending and hold it to the tie.

The location of the fastenings F between the positions of the ties T is one of the distinctive features of the invention since it provides for placing both the rail and the anchoring rods under tension thereby to secure excellent bearing between R and T 130

prior to concreting, also maximum flexing of the rail between the tie locations in such a way that the rail will not creep or move longitudinally, and at the same time preventing a wave motion in the rail under heavy moving loads due to its primary loading and continuous beam effect. In connection with the fastening means for the rails it may be pointed out that the clips 8 are held on the arms of the yokes 6 by the nuts 8^a which force the clips into rigid binding engagement with the rail flanges, thereby securely holding the rail in position. In this connection, however, it may be pointed out that the pulling together of the rail and anchor members 4 between the ties is mainly accomplished through the medium of the adjustable anchor 7 carrying the nut 7^b, but after the concrete C has been filled around the tie anchoring structure below the rails and allowed to set or harden, further clamping pressure may be exerted through the medium of the clips 8 and nuts 8^a to bring the rail down on the concrete to compensate for shrinkage in the latter.

After the structure has been assembled as described in the foregoing manner it will of course be understood that the concrete C is filled in and around the ties T, tie footings T' as well as about the reinforcing members 2, anchoring rods 4 and the rail fastenings F thereby providing a rigid bed for the entire structure. It may be also pointed out that the concrete is tamped solidly beneath the bottoms of the rails between the ties T so that the rails between the ties are supported on the concrete bed itself, the later pulling down of the clips 8 taking care of concrete shrinkage.

Figures 4 and 5 illustrate a different form of rail fastening device to serve the identical purposes of the foregoing arrangement designated generally as F'. This type of fastening includes a pair of adjustable bolts 11 which are united by a cross member 12 having an intermediate rail bearing portion 13 which is formed to bear on the underside of the base of the rail and bears on shoulders on bolts 11 or is arc welded thereto while the tips or outer ends of the wings thereof provide fulcruming shoulders 14 for the rail engaging clips 15. When the nuts 16 on the threaded ends of the bolts 11 are tightened up, the clips 10 will be forced downwardly into firm engagement with the rail flanges. The method of anchoring the fastening F' is similar to the method of securing the other form of fastening, and to that end the lower ends of the bolts 11 are provided with nuts 17 for engaging with a cross-tie 18 which engages the anchoring rods 4.

Figures 6 and 7 show a further modified form of rail fastening F² wherein the bolts 11^a have collars 19 welded thereon for supporting the cross member 20 which is prefer-

ably of a formed casting and of cross sections as shown in Figures 6 and 7. This yoke has an intermediate portion engaging the bottom of the rail and the ends of the wings thereof also constitute fulcruming shoulders 21 for 70 the clips 15^a so that when the nuts 16^a are tightened the clips will be forced against the rail flanges.

Figures 8 and 10 illustrate the type of clip 15 employed in Figures 4 to 7. As will be observed from these figures, the upper face of the clips may be formed with a ratchet portion 15^b for engaging with a corresponding ratchet face on the underside of the nut 16 to provide a nut locking action 80 in conjunction with the clips.

It will also be observed that the clips 15 operate in conjunction with a suitable adjustable washer either of the type shown in Fig. 9 or Fig. 11. In Figure 9, the washer 22 is of rectangular formation with the hole 22^a therein arranged eccentrically so that any one of the four sides of the washer may be placed against the edge of the foot flange of the rail to take up the space between the bolt on which the clip is mounted and the edge of the rail thereby to effectively prevent lateral movement of the rail on the ties or concrete and allow of adjusting said rail as the gage side wears. Figure 11 shows 95 a pentagonal washer 23 with the hole 23^a thereof also located eccentrically, thereby to provide five sides to the washer all of which are located at different distances from the axis of the hole. This washer gives a wider 100 range of adjustment.

Figures 12 and 13 shows another form of circular rail clip 24 having a projecting portion 25 adapted to bear on the rail while the flange portion 26 is adapted to bear on the concrete C.

Figures 14, 15 and 16 illustrate different ways of providing a rigid track structure in connection with an old concrete bed C'. In these views the tie portions T² need not extend from one rail to the other but are mounted on suitable supports S which may be either another rail section or other convenient support which rest upon the surface of the old concrete bed C'. According 115 to this type of installation, it is necessary to provide the old concrete bed with a hole or socket 27 adapted to receive a portion of the rail fastening means.

The type of rail fastening means shown in Figure 14 is designated generally as F³ and the same includes a bolt member which is doubled upon itself to provide a shank portion 28 which is fitted into the socket or hole 27 and then the hole grouted with concrete 120 thereby to firmly anchor the fastening in place. The arm portions 29 of the fastening F³ are adapted to receive the rail flange engaging clips 30 and also receive the nuts 31 for pressing the clip toward the rail 130

flange. This construction also illustrates a further means for providing the fulcruming element for the clip. That is to say, a fulcruming member 32 of substantially rectangular formation and having a bolt engaging portion 33 is held to the clip before the concrete fill is placed in position by means of a wire 34 or its equivalent. After the fastening has been firmly anchored in the old concrete bed and the rail placed under tension through the medium of the clips 30, concrete C² is filled in on top of the old concrete thereby to envelope and surround the ties T² and their supports and also envelope the fastenings F³. When the concrete has set, the fulcruming frames 32 will also be rigidly embedded in position and the manipulation of the nuts 31 may then force the clips 30 into additional binding engagement with the rail flanges.

In Figure 16, the rail fastening is designated in its entirety as F⁴ and comprises the spaced bolt members 36 which fit in the sockets 27 and are grouted therein for anchoring purposes. In this form the clip fulcruming members 38 have their lower ends resting upon the old concrete C' while their upper ends form a bearing or fulcrum for the clips 39.

The arrangement provided in Figs. 14, 15, and 16 illustrates how the rails may be anchored just above an old concrete bed without blasting the same out. In these cases, the running rails R are first alined laterally and then the anchor bolts are grouted in the holes or sockets drilled in the old concrete so that when the clips and nuts are applied to the bolts the running rails may be clamped down against the tie elements which are supported on the old concrete bed, giving the rail R its primary loading and continuous beam effect.

The manner of arranging the tie elements T at rail ends is illustrated in Figure 17. As will be observed from this figure the said tie elements are located adjacent the ends of the rails R and the abutting faces of the rail ends are welded together at W², thereby providing in effect a continuous rail. The said tie elements T are supported on an inverted old rail 40 which is disposed longitudinally with the running rails R, and the said old rail 40 constitutes not only the support for the tie elements but also the anchoring means for the type of rail fastening designated as F³ in Fig. 15 and therefore designated by the same character in Fig. 17. By uniting the rail ends through the medium of the weld W², it will be apparent that the downward pressure of the rail fastenings F³ on the rails will firmly hold the rail ends on the ties T in the same manner as the fastenings pull down the intermediate portions of the rails in the other forms of the structure.

From the foregoing it will be apparent that it is a feature of the present invention to provide means for rigidly securing track rails and track ties to each other by placing the rails under initial stress and placing the assembled construction in proper position before the concrete mass is put in place, and then tamping the concrete solidly beneath the bases of the rails between the points of metal to metal contact of the rails with the metal ties since the total weight of the structure is bolted together as one unit. In this way both the rails and the anchoring means as well as the fastenings are permanently placed under initial and permanent tension thereby to effectually counteract all yielding movements of the rails under moving loads.

Furthermore, the feature of tensioning the anchoring rods and rails before the concrete is poured enables all parts to be accurately alined and allow a major "take up" in the fastening means before the concrete is poured thus keeping the upper nut and bolt height to standard track and wheel clearances, and after concreting will permit the top nut and rail engaging clip to take up shrinkage to insure that the running rails will bear on the concrete between the ties which is not attained by any tie to rail fastening means. The cast steel clips together with the fulcruming means provided at the outer edges thereof not only serve to accurately hold the running rails but also permit of their removal in case replacement is necessary.

Another feature of the invention resides in the arrangement and location of the tie elements which for a minimum weight or expense of tie steel permits of a maximum effective distribution of the load on the concrete bed and thence on subgrade. That is to say, the steel bearings between the rails and the ties T are sufficient for the bearing power of the steel and can be equaled by the concrete contact under flanges and heads of ties T plus additional footing T' lengths as necessary and figurable according to the bearing power of concrete.

The concrete for a distance z or more, see Fig. 2, may be then said to safely support the required moving load and impact as placed over each tie T and it remains to spread the concrete transversely as at y, Fig. 1 sufficiently to safely place the total load on whatever type of soil or sub-grade forms the base foundation.

This construction thereby provides a figurable road bed from rail base to sub-soil, and also provides a rigid roadbed having rails at all ties in actual continuous and loaded contact therewith, by reason of which there is no surge or wave motion preceding each moving wheel (as present construction gives) thereby eliminating all motion, and all pound, and thus all wear between the

5 rail and tie, the moving load simply further compressing the rail and tie and the rail-to-tie contact as it passes over each tie and releasing the fastening's tension somewhat when passing over the point of rail fastening.

10 It is here to be noted that with this construction the rail cannot deflect excessively intermediate of ties T; first, because of the rail being a continuous beam; that is, a beam having at all supports restrained ends which reduces the deflection for any moving load up to as much as one fourth when the ends are fully restrained; and second, because the 15 concrete intermediate of ties T can be made to help bear the moving load since there is no actual motion, hammer, or wave at this point. Consequently, ties T may safely be placed at greater distances apart for the 20 given rail section for rail R or conversely lighter rails R may be used for the same train service and thus cheaper rails and rails having greater life (due to better manufacture) used.

25 It is obvious that the details are particularly arranged (1) for quick rail replacement by simply releasing the rail clips; (2) for ease of rail gage adjustment by releasing rail clips and resetting the adjustable washers; (3) for perfect rail alignment, vertical and transverse, prior to embedding in concrete since the whole construction as first bolted into a unit that can be shimmed to proper level and shoved to proper alignment 30 and then has weight enough to stay put while concrete is placed; (4) for minor elevation adjustments by releasing fastenings to allow of slipping liners between rails R and ties T and then replacing the initial 35 loading on each tie; (5) for permanency by providing locks for all fastening nuts.

40 This construction likewise insures the bearing of the rail R on the concrete (or tie plates laid therein) intermediate of the fulcrum ties T since the fastening can follow up the shrinkage of the set concrete surface, as tamped under rail intermediate of ties T.

45 An important feature of this invention is its ability to rigidly hold the rail R against all expansion and contraction since the combined pulls of all the fastenings place a sufficient and constant total load on the embedded ties T to make the resulting static friction between rails and ties (not counting intermediate concrete) much greater than the forces of expansion or contraction for all possible variations of temperature and the usually used sections of running rails R. My invention by the operation of this same 50 constant static friction or resistance effectually stops all rail creep or crawl, a particularly objectionable action of all present roadbed track, to stop which, many anitcreeper and rail clamp devices are being used.

55 This construction therefore accomplishes

70 benefits heretofore not achieved, and provides an easily adjustable, alignable and replaceable rail of a permanent way and at the same time a rail rigidly held and initially loaded while in use as the main member of such permanent way.

75 Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

80 I claim:—

1. A trackway construction including metallic ties, rails resting upon but not fastened to the ties, anchoring means arranged beneath the ties, and adjustable fastening devices for connecting the anchoring means with the rails.

85 2. A trackway construction including metallic ties, rails resting upon but not fastened to the ties, anchoring means arranged beneath the ties, and adjustable fastening devices for connecting the anchoring means with the rails, said fastening devices being adapted to place the rail under permanent load at points between the tie locations.

90 3. A permanent trackway including a concrete roadbed, a metallic tie consisting of an inverted rail section embedded in said concrete and having its base constituting a support for the rail, and rail fastening means embedded in the concrete at the side of said tie and having means spaced from the ties for forcing the rail into engagement with the tie.

95 4. A permanent trackway including a concrete roadbed, a metallic tie consisting of an inverted rail section embedded in said concrete and having its base constituting a support for the rail, and rail fastening means embedded in the concrete at the side of said tie and having means for forcing the rail into engagement with the concrete to compensate for shrinkage and drying.

100 5. A trackway construction comprising a permanent roadbed including ties and fastening anchoring means arranged below the ties and said ties and fastening and anchoring means adapted to be surrounded by concrete, rails resting upon said ties, rail fastening devices located between the ties and engaging with and connected to said rails and anchoring means and adapted to place the rail under permanent load, and means associated with said fastening means for increasing the permanent load imposed on the rails by the fastening devices thereby to force the same into engagement with the concrete after shrinkage.

105 6. A trackway construction including metallic ties, means for supporting said

110

115

120

125

130

ties, at a point above the maximum depth of the roadbed, rails resting on said ties, anchoring means arranged below the ties, adjustable rail fastening devices connecting the anchoring means with the rails to place both the anchoring means and the rail under permanent load; a concrete filling adapted to be placed around and about the ties; the anchoring means and beneath the bases of the rails; and rail engaging clips carried by said fastening means and adapted to pull the rail into contact with the concrete therebeneath to compensate for shrinkage.

7. A trackway construction including ties, rails resting upon the ties, rail fastening devices arranged between the ties for placing the rail under permanent load on each side of a tie location, said fastening devices comprising adjustable means for placing the rail under initial stress and other means for placing the rail under final stress.

8. A trackway construction including ties, rails resting upon the ties, anchoring elements arranged below the ties and disposed parallel to the rails, and a rail fastening device engaging both the rail and the anchoring means between the ties and comprising a yoke having arms adapted to be disposed at opposite sides of the rail base, a member engaging the said yoke, a cross tie engaging said anchoring members and also engaging the said member and constituting an abutment against which said member works in placing the rail under stress and the anchoring means under tension, and rail engaging fastenings carried by the arms of said yoke.

9. A trackway construction including a rail fastening device anchored in a concrete roadbed, a fulcruming member associated with said fastening device, and a rail engaging clip carried by the fastening device, and having a rocking bearing on said fulcruming member.

10. A trackway construction including a rail fastening device anchored in a concrete roadbed, a fulcruming member carried by the fastening device and having a portion projecting above the level of the concrete bed, and a rail clip adjustably fitted to said rail fastening device and having a portion thereof bearing on the fulcruming member and the opposite portion thereof adapted to bear against the rail flange to force the same downwardly against the concrete bed.

11. In a permanent trackway, metal ties consisting of old rail sections having their head portions welded together, rails supported on said ties to provide a metal to metal contact, concrete surrounding said ties and extending beneath the bases of the rails, fastening devices arranged between the ties and having means thereon for forcing the rail down into engagement with the

concrete therebeneath to provide a metal to concrete engagement between the rail and roadbed.

12. A permanent trackway construction wherein the structural elements are adjusted and assembled, prior to the filling in of the concrete comprising, ties, rails supported on the ties, anchoring rods arranged below the ties and paralleling the rails, a fastening device for initially placing the rail and anchoring means under stress, adjustable clips carried by the fastening devices for placing the rails under further stress and washers carried by the fastening devices for adjusting and holding the rails in position laterally on the ties.

13. A trackway including a roadbed, ties embedded in the roadbed, rails resting upon said ties, and anchoring means embedded in the roadbed and engaging the rails midway between the ties to produce a predetermined pressure between the rail and each tie.

14. A trackway including a roadbed, metallic ties embedded therein, and rails engaging said ties and having their ends welded together to form a continuous beam and fastenings at each side of the weld and midway between said ties for bending said rail ends downwardly over the ties.

15. In a trackway construction, a roadbed, a pair of metallic ties, rail ends supported on said ties, a weld for permanently connecting the rail ends, and fastenings embedded in the roadbed and adapted to place the rail ends including the weld under tension over said ties.

16. A trackway construction including metallic ties, rails resting upon the ties, anchoring means arranged beneath the ties, and adjustable fastening devices for connecting the anchoring means with the rails, said fastening devices being adapted to place the rail under permanent load at points midway between the tie locations.

17. A permanent trackway including a concrete roadbed, metallic ties consisting of inverted rail sections embedded in said concrete and having their bases constituting supports for the rail, and rail fastening means embedded in the concrete midway between the ties and having means for forcing the rail into engagement with the concrete between the ties to compensate for shrinkage and drying.

18. In a permanent trackway, the combination with the rails of rail supports, and means entirely independent of and arranged midway between said rail supports for engaging the rails and pulling down on the same to place the rails under load between the supports.

19. A trackway construction including spaced rail supports, rails resting upon said supports, and combined rail tensioning and rail fastening means independent of and ar-

ranged between the ties for placing the rails under stress between said ties.

20. A trackway construction including ties, rails resting upon but not fastened to said ties, anchoring means arranged between the ties, and devices for connecting the anchoring means with the rails at a point between the ties.

21. A trackway construction including ties spaced apart, rails resting upon the ties but not fastened thereto, anchoring means arranged beneath and between the ties, and devices for connecting the anchoring means with the rails between the ties for placing the rail under tension.

22. A permanent trackway construction including a concrete road bed, metallic ties embedded in said concrete roadbed, and rail fastening means embedded in the concrete between the ties and having means spaced from the ties for forcing the rail into engagement therewith.

23. A trackway construction including a concrete roadbed, a rail fastening device anchored in said roadbed, a fulcrumming member carried by the fastening device and having a portion projecting above the surface of the concrete bed and a rail clip carried by said rail fastening device and having a portion thereof bearing on the fulcrumming member and the opposite portion thereof bearing against the rail flange to force the same downwardly.

24. A trackway construction including a concrete roadbed, ties spaced apart in said roadbed, and fastening devices anchored in the concrete roadbed and having means for engaging the rails, for spacing the rails transversely of the trackway in predetermined increments and also placing the rails under tension.

25. A trackway construction including spaced non-elastic ties, rails mounted on said ties, and rail flexing means located at opposite sides of each tie for insuring the rail functioning as a continuous beam for carrying rolling loads.

26. A trackway construction including spaced non-elastic ties, rails resting upon said ties and anchoring means engaging the rails between the ties to produce rail flexure between the same.

In testimony whereof I hereunto affix my signature.
